Lellers Patent

The Schools are referred to in their Letter Patent and making part of the same containing a description of the works of the said Elmorea Lester, himself of his method of making moulds for casting iron vessels of any description.

Take two pieces of fine grained well seasoned hard timber, each of the length of the screw intended, and of a corresponding thickness as, for instance for a screw four feet long. Take two pieces of timber of the quality aforesaid, each four feet long, two and one half inches thick and four and one half inches wide, lay them together with a close joint, then fasten in each piece two pins, each of one inch in length. Then bore holes in each piece to receive the projecting pins. Then fasten the pieces together and reduce them to three inches diameter for two feet and a half in length. Then reduce the square to four inches square for two inches in length and reduce sides, the other eight inches, to a point from the square then the part on which the screw is to be cut being two and one half feet in length must be made perfectly smooth and round. Then cut the upper half inch wide, and three eighths of an inch deep, leaving the space of the same width as the iron or thread and also leaving the thread about the two and thirtieth part of an inch travelling. Then take two boxes made of boards, each five feet long fourteen inches wide and one foot deep, fill them with the best of sand then take the mould part prepared as aforesaid and mould one half in each box, with perfect exactness. Then put the boxes together leaving a hole in the upper box at the lower end of the square of the screw to run the mould in at, and the mould is completed. Thus by taking parts in proportion to the above any screw of similar dimensions may be cast, and by varying the proportion screws of any dimensions may be cast.

McClayton, C. J. (1970) *Chloroxylon swietenia* (Walter) (36 mm) (Savanna, May 1970) (2600 m.s.n.m.)
